[57] CLAIM

The ornamental design for a manure holding tank, as
shown and described.

DESCRIPTION

FIG. 1 is a top plan view of manure holding tank embodying my new design;
FIG. 2 is a bottom plan view thereof;
FIG. 3 is a right side elevational view thereof, the left
side being a mirror image of the right side shown;
FIG. 4 is a rear elevational view thereof; and
FIG. 5 is a front elevational view thereof.
